UNITED STATES PATENT OFFICE.

AUGUST BOUCHERY, OF NEW YORK, N. Y., ASSIGNOR TO WALLACE NOVELTY COMPANY, OF NEW YORK, N. Y., A CORPORATION OF NEW YORK.

DESIGN FOR A LIGHTING-FIXTURE.

47,218.

Specification for Design.

Patented Apr. 13, 1915.

Application filed December 30, 1914. Serial No. 879,811. Term of patent 14 years.

To all whom it may concern:

Be it known that I, AUGUST BOUCHERY, a citizen of the United States, residing in the borough of Brooklyn, county of Kings, city and State of New York, have invented a new, original, and ornamental Design for a Lighting-Fixture, of which the following is a specification, reference being had to the accompanying drawing, forming a part thereof.

In the drawing Figure 1 is a side elevation; and Fig. 2 is a plan view.

I claim:

The ornamental design for a lighting fixture as shown.

AUGUST BOUCHERY.
